UNITED STATES PATENT OFFICE

2,487,992

KNIFE SHARPENER

Walter A. Swigart, Chicago, Ill.

Application June 13, 1947, Serial No. 754,324

4 Claims. (Cl. 51—205)

1

This invention relates to certain new and useful improvements in knife sharpeners.

More particularly, the invention relates to a sharpening device for sharpening the cutting edges of the blades of a paper cutter and trimming machine. As such an invention has for its principal object the provision of an improved construction of this character, it will be highly efficient in use and economical in manufacture.

As the knives of a paper cutting and trimming apparatus usually are of substantial weight which makes it difficult to handle the blade for sharpening purposes, I have devised a device which may be supported upon the blade with the sharpening elements at a proper inclination with respect to the beveled cutting edge portion of the blade with ease and with the greatest degree of efficiency during the sharpening operation and the minimum degree of danger to the operator.

Another object of my invention resides in the manner of holding the sharpening elements within a holder and for locating these elements properly with respect to the beveled cutting edge of the blade.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention in applied position upon a blade;

Fig. 2 is a sectional detail view taken substantially on line 2—2 of Fig. 3; and

Fig. 3 is a view of the blade engaging surface of my sharpening device.

The several objects of my invention are accomplished by the preferred form of construction shown in the accompanying drawings and in which a holder is indicated at 10. This holder includes a back plate 11 from which extend integral side flanges 12 and intermediate flanges 13. The flanges 12 together with the flanges 13 provide with the back plate 11 separate channels 14 within which are adapted to be positioned the sharpening elements 15. These sharpening elements 15 may be formed of any approved material and are preferably whetstones.

The sharpening elements are yieldably held within the channels 14 by means of suitable spring leaves 16 disposed between the sharpening elements and the flanges 13 and of a sufficient resiliency to yieldably urge the sharpening elements 15 against the flanges 12.

2

These sharpening elements are releasably latched in the channels 14 by means of a retainer plate 17 having extending therefrom a binding screw 18 projecting through a slot 19 formed in the holder 10 between the flanges 13. On this binder screw is a latch nut 20 serving to latch the retainer plate 17 in an adjustable position with respect to the sharpening elements 15.

This retainer plate has an edge portion 21 provided with a substantially flat outer surface 22 which is adapted to engage the flat surface 23 of the knife blade 24 being sharpened.

A guiding head is indicated at 25 and comprises a body portion 26 positioned in a slot 27 formed in the back plate 11 between the upper end portions of the flanges 13. Secured to this body 26 as at 28 is a plate 29 carrying an adjustable screw 30. This guiding head 25 is pivotally connected by a pintle pin 31 to the flanges 13. The guiding head 25 includes a socket 32 in which is adapted to be mounted a guide block 33 or a whetstone (not shown), the latter being of the same size and shape as the guide block 33 whereby it may be substituted for the block 33 for reasons hereinafter set forth.

This block 33 is clamped within the socket 32 by means of a face plate 32' secured to the guiding head 25 by means of screw bolts 34.

The guide block 33 has a portion thereof removed to provide an open area 35 whereby when the sharpener is mounted upon the blade 24 the tip edge 36 of the cutting edge portion of the blade will be disposed at some point within the area 35 free from contact with the block 33.

To complete the invention there may be engraved, stamped, or impressed upon the plate 11 a scale 36', the lines of which may be numbered as at 37 and these lines may be spaced a predetermined distance apart so as to locate the flat surface 22 in close position with respect to the point of merger between the flat surface 23 and the beveled edge portion 23' of the blade 24, it being pointed out that this bevel 23' varies in different types of cutter blades.

In use after the retainer plate 17 has been properly adjusted for proper engagement with the flat surface 23 of the blade 24, the holder is mounted upon the blade 24 with the guide block 33 engaging the blade 24 in the manner shown in Fig. 2 and with the whetstones 15 flatly engaging the beveled edge 23'. By grasping the holder 10 between the fingers and the thumb the sharpener may be readily and conveniently reciprocated over the cutting edge portion of the blade 24 until a proper cutting edge has been restored

to the blade 24. Should the whetstones become worn they may be removed from their seated positions in the channels 14 and reversed or replaced by new whetstones.

After the sharpening operation has taken place there will be found to exist upon the cutting edge 36 minute burrs which should be removed. This is accomplished by removing the guide block 33 and replacing the same with a whetstone or the like and then reciprocating the holder relative to the blade until the burrs have been removed.

It will be apparent that my improved knife sharpener can be operated with the minimum degree of effort on the part of the operator with the minimum degree of possible injury to the operator, the latter resulting from the fact that the sharpening device by virtue of its guiding head positioned upon the blade cannot be readily displaced by accident or otherwise during the sharpening operation.

The sharpening elements are arranged in the holder in a manner such as to permit ready removal thereof for repair or replacement.

It will be also apparent that the retainer plate 17 in its function to properly position the sharpening elements with respect to the beveled portion 23 of the blade 24 serves to properly guide these sharpening elements at a proper inclination with respect to the blade 24 whereby an accurate beveled cutting edge will be maintained.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A knife sharpener comprising a holder, sharpening elements carried by the holder, means for removably mounting the sharpening elements within the holder and including an element adapted to engage the flat side of a knife blade for positioning the sharpening elements upon the beveled edge portion of the cutting edge of said knife blade, and a guide head pivotally carried by the holder and having means adapted to en-

gage the flat surface of the blade opposite the beveled edge of the knife.

2. A knife sharpener comprising a holder, sharpening elements carried by the holder, means for removably mounting the sharpening elements within the holder and for positioning the sharpening elements upon the beveled edge portion of the cutting edge of a knife blade, a guide head pivotally carried by the holder and having means adapted to engage the flat surface of the blade opposite the beveled edge of the knife, and means for adjusting said guide head relative to said blade.

3. A knife sharpener comprising a holder, sharpening elements carried by the holder, means for removably mounting the sharpening elements within the holder and for positioning the sharpening elements upon the beveled edge portion of the cutting edge of a knife blade, a guide head pivotally carried by the holder and having means adapted to engage the flat surface of the blade opposite the beveled edge of the knife, said retainer plate having means for adjustment relative to said sharpening elements, and means for adjusting said guide head relative to said blade.

4. A knife sharpener comprising a holder providing a channel, a guide block pivotally carried by said holder, a sharpening element mounted in said channel, a wall of said holder providing an elongated slot, a retainer bar extending transversely of the element, a screw extending through the slot and bearing upon said wall and having connection with the bar to draw the bar into clamping engagement with the element to clamp said element in said channel, said bar and said guide block having portions engaging a knife on opposite sides thereof with the element bearing upon an edge of the knife to be sharpened to guide movement of the holder relative to said knife edge.
